UNITED STATES PATENT OFFICE.

ADONIRAM JUDSON HENDERSON, OF TORONTO, CANADA.

CINDER-SIFTER.

SPECIFICATION forming part of Letters Patent No. 521,344, dated June 12, 1894.

Application filed January 9, 1894. Serial No. 496,263. (No model.)

To all whom it may concern:

Be it known that I, ADONIRAM JUDSON HENDERSON, official court-stenographer, of the city of Toronto, in the county of York, in the Province of Ontario, Canada, have invented certain new and useful Improvements in Cinder-Sifters, of which the following is a specification.

My invention relates to improvements in cinder sifters and the object of the invention is to devise a cinder sifter into which the ash pan for the stove or furnace may be introduced, filled with the ashes and cinders, so as to form part of the sifter and withdrawn after the ashes and cinders are sifted, with only the cinders, and thereby absolutely avoid any dust whatsoever either by pouring the ashes and cinders into the sifter or from the cinder shifter itself during its operation and it consists essentially of a wire screen for the most part preferably cylindrical provided with solid segmental ends journaled on the central crank spindle and having an opening made in the flat portion of the cylinder, which is closed by the ash pan, a hopper being provided for conducting the ashes into the ash receptacle and the whole of the parts being completely inclosed by a suitable case and the partial cylindrical screen being operated as hereinafter more particularly explained.

Figure 1, is a perspective view of my cinder sifter, portion of the front and door being broken away to exhibit the interior construction. Fig. 2, is a cross sectional detail showing the manner of connecting the pan to the flat portion of the wire screen cylinder.

In the drawings like letters of reference indicate corresponding parts in each figure.

A, is a case, rectangular in form, and completely inclosing at the top the wire screen, B, which is cylindrical for the most part and is provided with a flat side. The wire screen is attached to the segmental ends, b, which are made of wood lined on the inside with sheet metal, or of metal.

C, is a central spindle having a crank, c. The spindle, C, extends through the segmental ends to which it is secured and is journaled in the ends of the case, A.

D, is a pivoted link provided with a jaw, d, which is swung over the crank as shown and

is designed to hold the screen, B, so that the flat side is undermost.

B', are portions of the screen, which extend across each end of the flat portion. 55

B'', are cross boards arranged slightly obliquely and secured to the segmental ends, b.

b', are metal strips, which are screwed to the lower side of the boards, B'', and are designed to form ledges to receive and support 60 the sides of the ash pan, E. The ledges, b', are shown arranged in step fashion, so as to provide for a greater or less width of ash pan, this of course depending whether they are stove pans or furnace pans. 65

F, is the hopper by which the ashes are guided into the ash receptacle, G.

H, is a door, which is held closed by a latch, h, fitting into the catch, h'.

a, is a strip of felt or suitable material, which 70 surrounds the edge of the opening in the case, A, covered by the door. This felt is designed to prevent the escape of any dust during the period that the cinders are being sifted.

Having now described the principal parts 75 involved in my invention I shall briefly describe the operation. The pan, E, after being taken from the ash pit of the stove or furnace is inserted in upon the ledges, b', and thereby completely incloses the wire screen. 80 The door, H, is then closed so as to prevent any dust coming out and the crank handle, c, is released from the link, D, and the handle is thrown around so as to bring the pan to the top as indicated by dotted lines. The handle is then swung to and fro, giving a shaking motion until all the ashes are removed from the screen whereupon the handle is swung around into the position shown in the drawings and locked by the link, D. After 90 a short period the door may then be opened and the ash pan removed with the cinders.

It will be seen that my cinder sifter is arranged to accommodate various sizes of pans, the wire screen ends, B', being of such a width, 95 so that their inner edges come over the smallest sized pan. If the pan is large of course the wire netting portions, B', will also permit of the ashes to be thoroughly screened.

From this description it will be seen that I 100 provide a very simple, cheap and effective cinder sifter by which all dust is avoided in re-

moving the ashes from the stove to the cinder sifter and separating the cinders from such ashes. It will also be understood that immediately upon the ashes being separated from the cinders and the screen thrown around into the position shown in the drawings the cinders will be precipitated into the ash pan ready to remove.

What I claim as my invention is—

- 10 1. In a cinder sifter, a completely incased wire screen of substantially cylindrical shape, means for clamping the open mouth of an ash pan against the side of the screen, and means for reversing the screen and imparting a vibratory movement thereto whereby the ashes will be sifted from the pan but cinders will be retained therein, substantially as described.
- 15 2. The combination with the wire screen, B, attached to the segmental ends, b, and pro-

vided with a central spindle, C, journaled in the case A, and having a crank handle, c, of the boards B" extending longitudinally of said screen, and having ledges adapted to engage the flanges of an ash pan, substantially as described.

3. In combination, the rotating wire screen B attached to the segmental ends and having an opening in one side, boards extending parallel with each other upon opposite sides of the opening, a screen connecting said boards, and means for clamping the mouth of an ash pan against said screen, substantially as described.

ADONIRAM JUDSON HENDERSON.
